Attorney

UNITED STATES PATENT OFFICE.

GEORGE H. TAYLOR, OF NORFOLK, VIRGINIA.

CARD CLASP.

Application filed August 26, 1927. Serial No. 215,587.

This invention relates to a card clasp, and particularly to a releasable holder adapted to support a card or similar article from a shank or handle member.

5 In previous constructions for this purpose it has been necessary to force the card into the clasp against the spring tension thereof which tore and mutilated the edge of the card so as to prevent its continued use, for instance in a price card system for which the present invention is especially designed. Further, in the use 10 of a wire clasp there is not sufficient base to support the card against rocking or tilting movement, while the usual clamping jaws are not of proper area to retain assembled cards in their proper relation as the price unit is held by the clasp. It is also very 15 desirable to avoid any construction requiring both hands of the operator for opening the clasp, and to provide a form where the clasp may be opened by one hand while the card is inserted therein by the other hand.

To avoid these objections I have provided 20 a flat metal structure comprising an elongated shank having at its upper end a broad fixed jaw from which a loop portion forms a supporting base for a card and is bent upwardly to form a movable jaw which terminates in an outwardly projected operating plate. These jaws are normally inclined to 25 a vertical plane when the shank is inserted in a container, such as a basket, box or barrel, but inward pressure upon the operating plate 30 opens the movable jaw and brings the loop into a vertical plane parallel to the shank which permits the most convenient application or insertion of the card. Upon release 35 of pressure this loop automatically assumes its inclined position and the operating end 40 of the movable jaw is alined with the shank to permit the application of opening pressure by two fingers of the operator's hand.

The invention has for an object to provide 45 a novel and improved construction of card clasp provided with a shank having a fixed jaw at its upper end and a broad downwardly looped portion for a card seat and having a movable jaw opposite the fixed jaw and terminating in a depending operating plate parallel to the shank.

A further object of the invention is to form 50 the clasp of a single piece of flat spring metal comprising an elongated shank having a fixed jaw and a downward loop with an opposite movable jaw terminating in an out-

wardly deflected operating plate parallel with the shank, whereby pressure upon said plate separates the jaws and changes the position of the loop relative to the shank to permit 55 convenient insertion of a card.

Another object of the invention is to present an improved clasp having a shank formed of flat material with its upper portion bent into a U-shaped loop provided with 60 rebent jaws engaging the loop and then deflected therefrom to form a shank and opposite site operating plate.

Other and further objects and advantages of the invention will be hereinafter set 70 forth and the novel features thereof defined by the appended claims.

In the drawing—

Figure 1 is a perspective of the invention;

Figure 2 is a side elevation thereof; 75

Figure 3 is a detail section of the clasp opened;

Figure 4 is a section on line 4—4 of Figure 2; and

Figure 5 is an elevation of a modified application of the invention.

Like numerals refer to like parts in the several figures of the drawing.

This invention is adapted for a wide field of application and in the form shown in 85 Figures 1 to 4 the numeral 10 designates an elongated shank which may be of any desired size or configuration and forms the support or handle for the clasp at its upper end. This clasp comprises the fixed jaw 11 90 formed of flat material bent upon itself and downwardly into the loop 12 which at its lower portion provides a flat wide support 13 to prevent tilting of the card 14 resting thereon. 95

The movable jaw 15 extends upward from this support and is bent upon itself to form an outwardly projecting operating plate 16 disposed in alinement with the shank held by one finger when depressing the plate by another finger to open the jaw. Each of the jaws at the bend therein is constricted, as at 17, to engage the outersurface of the contact faces 18 and provide substantially parallel walls for the loop 12. This loop is preferably disposed at an angle to the shank to incline the card for convenient reading when placed therein, and the depression of the operating plate swings this loop into a substantially vertical position which renders 110 it readily accessible for the insertion of a card, as shown in Figure 4.

The card retained by the clasp may be of any desired character and is shown in Figure 1 as comprising the base card 14 having a lug 21 which overlaps the interlocked price cards 22 formed in accordance with my Patent No. 1,529,968 dated March 17, 1925. When used in this connection the clasp jaws clamp the cards in position and retain the price unit against accidental displacement.

10 Instead of supporting the price unit mentioned the clasp may be used to retain an enlarged card, such as a fan 23 shown in Figure 5, which is clamped by the clasp 24 constructed as before described, while the 15 shank 25 comprises a handle portion. This is very convenient for theater programs which require changing at intervals as new cards may be quickly applied to the clasp and avoid the expense and delay of providing 20 an entirely new fan for each change of program to be printed thereon.

It will be seen that the invention presents a simple, efficient and economically produced article of manufacture adapted to be bent 25 from a single piece of material. The clasp provides a wide base to support a card and firm clamping jaws parallel thereto which rigidly retain the card but permit its removal and insertion without damage by opening the 30 jaws.

The specific construction of the clasp has been herein shown and described but the invention is not confined thereto as changes and alterations may be made therein without 35 departing from the spirit of the invention as recited in the following claims.

What I claim is:—

1. A card clasp comprising a straight elongated shank having a rebent upper end contacting with the shank to form a fixed jaw, a substantially parallel portion bent upwardly from the base of the fixed jaw to form a movable jaw, and an operating plate extended downwardly and outwardly from the upper end of the movable jaw, the upper ends of both jaws being deflected outwardly in opposite directions to provide a curved inserting guide. 40

2. A card clasp comprising an upright elongated shank having a rebent upper end 50 contacting with the shank to form a fixed jaw, a substantially parallel looped portion bent upwardly from the base of the fixed jaw to form a movable jaw, and an operating plate extended downwardly and outwardly 55 from the upper end of the movable jaw, said looped portion being bodily deflected outward at an angle to the shank.

3. A card clasp formed of a single piece of flat spring metal comprising an elongated 60 upright shank having a rearward bend at its upper portion forming a fixed jaw which is deflected at an angle to the shank, a loop portion depending from said bend with substantially parallel walls, the outer of which 65 is provided with a bend at its upper edge to form an outwardly deflected movable jaw, and a plate projected outward from the last mentioned bend to produce an operating member, said loop portion being bodily deflected at an angle to the shank. 70

In testimony whereof I affix my signature.

GEORGE H. TAYLOR.
